UNITED STATES PATENT OFFICE.

GEORGE O. LEOPOLD, OF PHILADELPHIA, PENNSYLVANIA, ASSIGNOR TO NORTH BRO'S. M'FG. CO., OF PHILADELPHIA, PENNSYLVANIA, A CORPORATION OF PENNSYLVANIA.

DESIGN FOR A FRAME OF BENCH-DRILLS.

43,803.

Specification for Design.

Patented Apr. 1, 1913.

Application filed December 10, 1912. Serial No. 736,028. Term of patent 14 years.

To all whom it may concern:

Be it known that I, GEORGE O. LEOPOLD, a citizen of the United States, residing in Philadelphia, Pennsylvania, have invented a certain new, original, and ornamental Design for the Frame of a Bench-Drill, of which the following is a specification, reference being had to the accompanying drawing, forming part thereof.

The figure is a perspective view of the

frame of a bench drill, showing my new design.

I claim:—

The ornamental design for the frame of a bench drill, as shown.

GEORGE O. LEOPOLD.

Witnesses:

W.M. E. SHUPE,
W.M. A. BARR.
